(57) **CLAIM**

The ornamental design for a mobile phone, as shown and described.

DESCRIPTION

FIG. 1 is a front view of a mobile phone, showing the new design;

FIG. 2 is a back view of the mobile phone;

FIG. 3 is a left view of the mobile phone;

FIG. 4 is a right view of the mobile phone;

FIG. 5 is a top view of the mobile phone;

FIG. 6 is a bottom view of the mobile phone;

FIG. 7 is a top right perspective view of the mobile phone;

FIG. 8 is a bottom left perspective view of the mobile phone;

FIG. 9 is a front view of the mobile phone in a folded and closed state;

FIG. 10 is a back view of the mobile phone in the folded and closed state;

FIG. 11 is a left view of the mobile phone in the folded and closed state;

FIG. 12 is a right view of the mobile phone in the folded and closed state;

FIG. 13 is a top view of the mobile phone in the folded and closed state;

FIG. 14 is a bottom view of the mobile phone in the folded and closed state;

FIG. 15 is a top right perspective view of the mobile phone in the folded and closed state;

FIG. 16 is a bottom left perspective view of the mobile phone in the folded and closed state;

FIG. 17 is a front view of the mobile phone in a partially folded and sitting state;

FIG. 18 is a back view of the mobile phone in the partially folded and sitting state;

FIG. 19 is a left view of the mobile phone in the partially folded and sitting state;

FIG. 20 is a right view of the mobile phone in the partially folded and sitting state;

(Continued)

FIG. 21 is a top view of the mobile phone in the partially folded and sitting state;
 FIG. 22 is a bottom view of the mobile phone in the partially folded and sitting state;
 FIG. 23 is a top right perspective view of the mobile phone in the partially folded and sitting state; and,
 FIG. 24 is a bottom left perspective view of the mobile phone in the partially folded and sitting state.
